UNITED STATES PATENT OFFICE.

FREDERICK M. KEITH, OF SOMERVILLE, MASSACHUSETTS.

DESIGN FOR A CHEESE-CABINET.

SPECIFICATION forming part of Design No. 28,898, dated June 21, 1898.

Application filed April 28, 1898. Serial No. 679,142. Term of patent 7 years.

To all whom it may concern:

Be it known that I, FREDERICK M. KEITH, a citizen of the United States, residing at Somerville, in the county of Middlesex and State of Massachusetts, have invented and produced a new and original Design for a Cheese-Cabinet, of which the following is a specification.

The drawing represents in perspective a cheese-cabinet illustrating my design.

The leading feature of my design for a cheese-cabinet comprises a frame having trapezoidal end walls, each divided into two unequal trapezoidal panels, an upright rectangular back, and an inclined quadrilateral front subdivided into four quadrilateral panels.

The cabinet comprises a rectangular bottom a and top a' , an upright rectangular

back b , and an inclined front wall c , the latter being divided by upright and transverse moldings $c' c''$ into four quadrilateral panels $C C'$, while the ends d of trapezoidal form are divided by horizontal moldings d' into trapezoidal panels D and D' of unequal size. 20 25

Having fully described my invention, what I claim, and desire to secure by Letters Patent, is—

The design for a cheese-cabinet, substantially as herein shown and described. 30

In testimony whereof I have signed my name to this specification in the presence of two subscribing witnesses.

FREDERICK M. KEITH.

Witnesses:

JOHN G. ROBINSON,
M. E. CAREY.
